TIRE

Arthur C. Blankenship, Detroit, Robert F. Busch, St. Clair Shores, and William L. Shesterkin, Roseville, Mich., assignors to Uniroyal, Inc., a corporation of New Jersey

Filed Sept. 28, 1966, Ser. No. 4,058

Term of patent 14 years

(Cl. D90—20)

FIG. 1 is a perspective view of a tire embodying our new design, it being understood that the full-line portion is repeated throughout the circumference of the tire, shown by means of broken lines;

FIG. 2 is an enlarged, fragmentary, developed plan view of the full-line portion shown in FIG. 1;

FIG. 3 is a sectional view taken substantially on the plane indicated by the line 3-3 in FIG. 2; and

FIG. 4 is an enlarged fragmentary, elevational view of a part of the full-line portion shown in FIG. 1.

The dominant features of our design reside in those portions shown in full lines in the drawings.

We claim:
The ornamental design for a tire, substantially as shown and described.
